UNITED STATES PATENT OFFICE.

ROLLIN H. WIGGIN, OF EAST ORANGE, NEW JERSEY, ASSIGNOR TO H. B. WIGGIN'S SONS COMPANY, OF BLOOMFIELD, NEW JERSEY, A CORPORATION OF NEW JERSEY.

DESIGN FOR SHEET MATERIAL FOR COVERING WALLS AND BOOKS.

48,919.

Specification for Design.

Patented Apr. 18, 1916.

Application filed December 15, 1915. Serial No. 67,070. Term of patent 14 years.

To all whom it may concern:

Be it known that I, ROLLIN H. WIGGIN, a citizen of the United States, residing at East Orange, in the county of Essex and State of New Jersey, have invented a new, useful, and ornamental Design for Sheet Material for Covering Walls and Books, of which the following is a specification, reference being had to the accompanying drawing, forming a part thereof.

The figure is an elevation of sheet material for covering walls or books, showing my new design.

I claim:

The ornamental design for sheet material for covering walls and books, as shown.

ROLLIN H. WIGGIN.

Witnesses:

JOHN R. WINANS,
ANGELA C. BURKE.
